United States Patent Office

Des. 226,258
Patented Feb. 6, 1973

226,258

HOOK

Jordan I. Rotheiser, Highland Park, Ill., assignor to Selfix, Inc.

Filed Mar. 15, 1971, Ser. No. 124,655

Term of patent 14 years

Int. Cl. D8—08

U.S. Cl. D8—246

FIG. 2

FIG. 1

FIG. 3

FIG. 4

FIG. 5

FIG. 6

FIG. 1 is a side perspective view of a hook showing my new design;

FIG. 2 is a top view;

FIG. 3 is a bottom view;

FIG. 4 is a front elongated view;

FIG. 5 is a side elevational view, the side opposite being a mirror image thereof; and

FIG. 6 is a front elevational view.

The broken lines are for illustrative purposes only.

I claim:

The ornamental design for a hook, substantially as shown and described.
